Primary Examiner — David Muller(74) *Attorney, Agent, or Firm* — Matthew A. Pequignot; Pequignot + Myers LLC(57) **CLAIM**

The ornamental design for a thermal pack, as substantially shown and described.

DESCRIPTION

FIG. 1 is a perspective view of a thermal pack showing the new design.

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

Structure illustrated in broken lines is provided to illustrate the environment of the invention but is not otherwise part of the claimed design.

1 Claim, 4 Drawing Sheets# US D728,810 S
